UNITED STATES PATENT OFFICE.

WILLIAM H. HEULINGS, JR., OF PHILADELPHIA, PENNSYLVANIA, ASSIGNEE TO THE
J. G. BRILL COMPANY, OF PHILADELPHIA, PENNSYLVANIA, A CORPORATION OF
PENNSYLVANIA.

WINDOW-FRAME.

1,233,667.

Specification of Letters Patent. Patented July 17, 1917.

Application filed February 25, 1913. Serial No. 750,628.

To all whom it may concern:

Be it known that I, WILLIAM H. HEULINGS, Jr., a citizen of the United States, residing in Philadelphia, Pennsylvania, have 5 invented certain Improvements in Window-Frames, of which the following is a specification.

The object of my invention is to construct a window frame in such a manner that the 10 sash can be readily removed, when desired, and which will hold the sash tightly in position, preventing it from rattling and will also hold it in such a manner as to prevent air passing between the sash and the frame 15 when the sash is in the closed position.

My invention is particularly adapted for use in railway passenger cars, but it will be understood that it can be used in any place where it is desirable to quickly remove the 20 sash or to prevent the sash from rattling in the frame.

In the accompanying drawings:—

Figure 1 is a perspective view showing the upper portion of the frame in section 25 and illustrating my invention;

Fig. 2 is a vertical sectional view on the line *a—a*, Fig. 1;

Fig. 3 is a transverse sectional view on the line *b—b*, Fig. 2;

Fig. 4 is an enlarged sectional view on the line *b—b*, Fig. 2, showing each sash in section and the central portion of the sash cut away; and

Figs. 5, 6, 7, 7^a and 8, are views illustrating modifications of the invention.

Referring to the drawings, 1—1 are the vertical posts of a passenger car separating one window opening from another. These posts are T-shaped in cross section. 2 is the 40 lower sash of the window and 3 is the upper sash. The frame of each window is formed of sheet metal secured to the post 1, as clearly illustrated in Fig. 4, one side being rigidly secured to a post and the other so 45 secured thereto that a portion of the frame will yield to allow for the insertion of the sash and to hold the sash firmly in position. The rigid portion consists of a metal plate

5 having longitudinal grooves 6 and 7 therein 50 forming ways for the upper and the lower sash. This plate is bent at 8 at the outer end so as to rest against the outer portion of the post 1 and is secured thereto by screws, or other fastenings. The inner end of this 55 plate is bent to form a guideway 9 for a

curtain rail and is also bent so as to form a face 10, which extends across the inner portion of the posts, as illustrated in the drawings, forming the finish of the division strip between the window openings. The ends 11 60 of the sash 2 and 3 are beveled, as shown, and are preferably sheathed with a metal strip 12. The plate 5 is bent to form grooves 6 and 7 which are shaped to correspond with the beveled edges of the sash. Shoulders 13 65 and 14 are thus formed on the frame and the inclined portion of the sash is such that the sash bears against these shoulders, making a tight joint at the longitudinal edge of the sash. The plate is also beveled at 15 so 70 as to allow the sash to be readily inserted in position.

The frame, at the opposite side of the window openings, has yielding sections, which allow for the insertion or removal of 75 the sash.

16 is a plate which has a portion 16^a extending under the portion 10 of the plate 5 and both portions are secured to the post 1 by screws, or other fastenings. The plate 16 80 is bent to form a pocket or guideway 17 for the opposite end of the curtain rod mentioned above and is beveled at 18, being also beveled in the opposite direction at 19 to form the base of the longitudinal groove 85 into which extends the edge 20 of the lower sash. The end 21 of the plate 16 is bent outward, as shown, to form a flange which underlaps the inward flange 22 of a diagonally arranged plate 23, which forms the 90 base of the vertical groove for the upper sash 3. The end 24 of this plate is turned to form a flange and underlaps the inwardly projecting flange 25 of a plate 26 which overlaps the edge of the post 1 and is secured 95 thereto by screws or other fastenings. The plate 23 is attached to a spring plate 27, as shown clearly in Fig. 4, and this plate 27 is attached to the post 1 at 28 by screws or other fastenings. This plate may be a continuous plate from top to bottom of the frame, or it may be made in sections, as desired.

Thus it will be seen that the plates 16 and 23 are yieldingly attached to the post and 105 that they have a tendency to spring outward and, consequently, to hold the sashes 2 and 3 firmly against the opposite plate 5 and due to the shape of the edges of the sash hold the sash firmly against the flat surfaces 110

13, 14, 22 and 25, making each sash air tight at the vertical edges. Yet the pressure of these yielding plates is not sufficient to prevent the easy sliding of the sash when it is desired to raise or lower them.

If it is desired to remove one of the sashes, say the lower sash 2, from the frame, it is raised slightly and the lower portion is seized adjacent the rigid plate 5, that is, at 10 the right hand of Fig. 3, and pulled toward the inside of the car in the direction of the arrow in that figure. The inward inclination of the face of the groove 6 on the plate 5 will cause the sash to travel bodily toward 15 the left and flex the plate 16 on the opposite post casing inwardly sufficiently to allow the edge of the sash to clear itself from plate 5. The sash is then swung clear of the frame by pivoting it on the spring plate 16 20 until it is clear of the post and casing.

When it is desired to replace the sash, the plate 23 is depressed to allow the edge of the upper sash to pass the high point, after 25 which it will drop in position and the same method can be used in placing the lower sash in position, the bevel portion 18 of the plate 16 engaging the sash and causing the plate 16 to yield until the edge of the sash passes into the groove, of which the portion 30 19 of the plate forms the base.

In some instances, the plates at each side of the window opening, which form the frame, may have yielding sections. Both plates may be shaped to conform to the sash 35 and may be rigidly secured in position, the thin metal plates having the necessary elasticity to hold the sash in position and thus make a substantially air-tight fit.

In Fig. 5, I have shown a modification in 40 which the grooves for the upper and the lower sash are formed by bending a single plate 28, attached to the base 1, at the inner end by its integral connecting piece 28^a, there being an outwardly projecting flange 45 29 which underlaps the inwardly projecting flange 30 on an angle plate 31, attached to the outer edge of the post. The flange 30 forms a portion of the sash groove and combined with the flange 29 forms a movable joint at this point and these flanges 29 and 30 combined with the sash form a 50 "weather" joint. The plate 28, in this instance, is continued and is bent to form the fixed grooved side members of an adjoining frame.

In Fig. 6, I have illustrated a modification in which three sashes, 32, 33 and 34 are used. The sash 32 rests against the yielding section 35 of the frame and there are independent yielding sections 36 and 37 for the sashes 33 and 34 respectively. Each of these sections is yieldingly secured to the post 1. The plate 38 at the opposite side of the post is so bent as to form the guides for the three 65 sashes.

In Fig. 7, I have illustrated a modification in which there is a single groove 39 to receive a single sash, the plate 40 being secured to the post 1 and bent to form the inclined portion and base of the recess 39. 70 The plate 40 is also provided with the curtain groove 17 previously described. Instead of surrounding the post 1 by a casing made up of the inflexible plate 5 and the flexible plate 16, each having their overlapping portions 10 and 16^a, the casing may be made as shown in Fig. 7^a, having both sides 75 28 yielding.

In Fig. 8, I have shown another modification in which coiled springs 41 are located 80 between a grooved plate 42 and the post 1 so that as the sashes are placed in position, the springs will yield, allowing the plate 42 to adapt itself to the sashes. The construction shown in Fig. 8 is not claimed herein, 85 but forms the subject matter of another application filed by me, the same being Ser. No. 39,299, filed July 12th, 1915.

By this construction, I not only provide for the ready and quick removal of the 90 sashes, but I also provide a construction which occupies but little space, consequently, the window openings can be of comparatively small size. The construction is substantial and not likely to get out of 95 order. Additionally it extends the range of ornamentation or trim of the posts, reduces the cost of manufacture of the parts and considerably simplifies the process of assemblage and dismemberment. 100

I claim:

1. A structure of the class described, the combination of a post, a plate secured to one end of said post and adapted to be moved against resilient resistance toward the side 105 of the post, a projection extending from the other end of the post, a recess in the plate combined with the projection to form a sash receiving guide-way.

2. A structure of the class described, the 110 combination of a post, a plate secured to one end of said post and having a resilient free end adapted to be moved against resilient 115 resistance toward the side of the post, a projection extending from the other end of the post, a recess in the resilient plate, the end of the resilient plate and the end of the projection overlapping to form a portion of the sash receiving guide-way.

3. A structure of the class described, the 120 combination of a post, a plate secured to one end of said post and adapted to be moved against resilient resistance toward the side of the post, a projection extending from the other end of the post, a recess in the 125 plate combined with the projection to form a sash receiving guide-way and a curtain groove formed in the plate adjacent the end of the post to which the plate is secured.

4. In a structure of the class described, 130

the combination of a post having an outer and an inner terminal, a plate rigidly secured to one terminal and having an inwardly movable and resilient free end extending toward the other terminal, and a projection extending from said last mentioned terminal and forming a portion of the guide for the sash.

5. In a structure of the class described, 10 the combination of a post having an inner and an outer terminal, a plate having a sash groove formed therein secured to the inner terminal of the post and extending toward the outer terminal, a plate secured to the outer terminal, the first mentioned plate having its free end resilient and movable to or from the post, the last mentioned plate coöperating with the first mentioned plate to form the groove for the sash.

20 6. In a structure of the class described, the combination of a pair of posts and casing plates therefor, one of said casing plates comprising a plate having one of its ends fixed to the post and a free end extending 25 between the terminals of said post, said free end being flexible and adapted to be sprung toward the post, another plate on the opposite post, a sash groove formed in each of said plates, a projection on the post to 30 which the flexible plate is secured extending toward the free end of said flexible plate, said projection forming a portion of the groove on said flexible plate for the sash.

7. In a structure of the class described, 35 the combination with a post having an inner and outer terminal, a grooved and flexible plate secured to one terminal and a flanged plate secured to the other terminal, the free end of the grooved plate coöperating 40 with the free end of the flanged plate to form a movable joint and the end of the flanged plate forming a portion of the sash groove.

8. The combination in a window frame, 45 of two vertical side members made of sheet metal bent into shape to form grooves for the upper and the lower sash; a post at each side of the window frame; one of the said side members being rigidly secured to the 50 post, the other side member being made in two sections yieldingly mounted; one section being secured to the inner end of the post and having an outwardly extending flange; a plate secured to the outer end of 55 the post and having an inturned flange; the other yielding section of the side member having an inturned flange overlapping the outturned flange of the yielding section of the side member and having an outturned flange 60 underlapping the flange on the plate secured to the outer edge of the post; and

yielding means for supporting the said section.

9. In a structure of the class described, 65 the combination of a post, one of the sides of said post being surrounded by a grooved plate, said plate having an extension at its inner end secured to the inner end of said post, a flange at its outer end secured to the outer end of the post; a grooved and flexible 70 plate on the opposite side of the post having an extension on its inner end secured to the inner end of the post, a flange on its outer end, a plate secured to the outer end of the post having an inwardly extending 75 flange, said flange being adapted to engage the flange on the outer end of the flexible plate.

10. In a structure of the class described, 80 the combination of a post, one of the sides of said post being surrounded by a grooved plate, said plate having an extension at its inner end secured to the inner end of said post, a flange at its outer end secured to the outer end of the post, a grooved and flexible 85 plate on the opposite side of the post having an extension on its inner end secured to the inner end of the post, a flange on its outer end, a plate secured to the outer end of the post having an inwardly extending flange, 90 a grooved plate extending between the plate secured to the outer end of the post and the flexible plate and having flanges engaging the flanges on said plates and a spring plate having one of its ends secured to said plate 95 and its other end secured to the post.

11. In a structure of the class described, 100 the combination of a post, one of the sides of said post being surrounded by a grooved plate, an inwardly extending flange on the outer end of said plate secured to the outer end of the post, an inwardly extending flange on the inner end of said plate secured to the inner end of the post, a pair of 105 flexible plates secured to the opposite side of the post, said plates forming grooves for the reception of sashes, the upper of said flexible plates having an outwardly extending flange, a plate secured to the outer end of the post having an inwardly extending flange adapted to engage the flange on the upper flexible plate and a plate supporting 110 said flexible plates with a flange on its inner end secured to the inner end of the post.

In testimony whereof, I have signed my 115 name to this specification, in the presence of two subscribing witnesses.

WILLIAM H. HEULINGS, JR.
